OTHER PUBLICATIONS

Nash, U.S. Appl. No. 62/620,100, filed Jan. 22, 2018, entitled "Tape Dispenser with Mount and Rotation Mechanism".

Primary Examiner — Elizabeth A. Albert

(74) Attorney, Agent, or Firm — 3M Innovative Properties Company; Eric E. Silverman

(57) **CLAIM**

The ornamental design for a tape dispenser, as shown and described.

DESCRIPTION

FIG. 1 is a perspective view showing the new design for a tape dispenser;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is a top view thereof; and,

FIG. 8 is a perspective view thereof with a tape.

The portions of the tape dispenser in FIGS. 1-8 shown in broken lines are included to show features that form no part of the claimed design.

1 Claim, 6 Drawing Sheets(56)
